ABSTRACT OF THE DISCLOSURE

A method and structure for building construction in which a first pair of opposed vertical, hollow, spaced apart columns is erected and then a second pair of opposed vertical, hollow columns is erected in spaced apart relationship to the first pair of columns. One or more horizontal cantilevered beams are then secured to each pair of columns with their outboard ends projecting outwardly beyond each of the columns so as to form an H-shaped frame. Prefabricated housing components can then be mounted on the extending arms of the beams and utility connections can then be mounted on the extending arms of the beams and utility connections can be made through the hollow columns with the H-shaped arrangement providing an open space between adjacent frames which permits installation of stairs and other appurtenances.

BACKGROUND OF THE INVENTION

This invention, in general, relates to low-cost prefabricated building construction and specifically relates to a simplified H-shaped type framework onto which pre-assembled housing components can be mounted.

DESCRIPTION OF THE PRIOR ART

Applicant is aware of the following prior art: Klein—U.S. 2,837,776, Hohla—U.S. 3,213,572, Stucky et al.—U.S. 3,377,755, Stucky et al.—U.S. 3,416,273. Of these references, both of the Stucky patents relate to a method of stacking prefabricated room elements on top of each other. The Klein patent relates the use of tension cables on a multistory structure. The Hohla patent discloses the utilization of columns and trusses for a multi-story building but lacks the simplicity, ease of construction and several of the specific features of applicant's structure as will now be described.

SUMMARY OF THE INVENTION

In the building industry in general and the housing industry in particular there is a well recognized need for low-cost, easy to erect housing due to the well known fact that construction costs have risen steadily in recent years. It is well recognized that the trend in this industry is toward prefabricating or preconstruction as much of the building at the factory as possible in order to avoid the considerable expense which is incurred when all of the construction is done at the construction site.

The present invention represents a decided improvement in this general area.

Thus, it has been found that by providing at least two pairs of spaced apart, hollow upright columns and securing at least one cantilevered beam to each pair of columns to form a generally H-shaped frame that prefabricated housing units, or for that matter, trailers can simply be lifted into place on the projecting ends of the beams in a simple and economical operation.

Utilizing the H-frame structure also provides an open deck space between the pairs of columns which is bounded by two of the housing units on its opposed sides and by the two pairs of columns at its opposed ends. This space has utility for stairways, common hallways, etc.

Accordingly, production of an improved building con-

2

struction of the character described becomes the principal object of this invention with other objects thereof becoming more apparent upon a reading of the following brief specification considered and interpreted in view of the accompanying drawings.

Of the drawings,

FIG. 1 is a perspective view of the improved building construction partially broken away.

FIG. 2 is an end elevation of the frame work showing the stairs and decks in place.

FIG. 3 is a side elevation of the improved framework taken from the left of FIG. 2.

FIG. 4 is a top plan view of the framework shown in FIGS. 2 and 3.

FIG. 5 is a partial end view taken from the left of FIG. 1 and showing the housing components in place on the framework.

FIG. 6 is a side elevation taken from the right of FIG. 1.

FIG. 7 is a detailed partial sectional view showing the means for mounting the housing components on the beams.

FIG. 8 is a partial sectional view showing the means for securing the housing components to the upright columns.

FIG. 9 is a partial sectional view showing the utility lines and their method of connection with the housing component.

FIG. 10 is a perspective view showing a modified form of the invention.

FIG. 11 is a plan view showing the framework for still another modified form of the invention.

FIG. 12 is a perspective view of the form of the invention shown in FIG. 11.

Considering first then FIG. 1, it will be seen that the framework of the improved building construction generally consists of two pairs of upright columns 11 and 12 and 13 and 14 and a plurality of cantilevered beams 15, 15.

The columns 11, 12, 13, and 14 are identical and are generally hollow and can either be concrete or steel or any other suitable material. Considering then the first pair of columns 11 and 12, it will be seen that these are simply mounted on a foundation F in conventional fashion and are spaced apart from each other with the distance between the columns being optional but in any event, being sufficient to enable stairways, railings, landings, etc. to be placed therebetween as will be described in greater detail.

Spanning the distance between columns 11 and 12 and projecting outwardly therefrom are cantilevered beams 15, 15 which may be of any suitable material having sufficient strength to support the housing components. These beams may be secured to the columns themselves in any known fashion and are spaced apart vertically a distance which is indicated by the height of the components placed thereon so as to form the required number of floors. In this regard, it should be noted that in the form of the invention shown in FIGS. 1 through 8, three beams have been utilized but it is believed apparent that any number of beams could be employed depending upon the number of floors desired.

This second pair of columns 13 and 14 are spaced apart from the first pair of columns and the distance is again determined to a large extent by the size of the prefabricated housing components to be utilized. It should be noted that applicant is not limiting this application in any way to any particular size or spacing. Likewise, while only two pairs of columns have been shown, it is believed apparent that more could be employed if desired or if required for supporting purposes.

It will be noted that by spacing the opposed pairs of columns in the manner described that an open area of

generally rectangular shape is provided therebetween. This space is intended to be filled by decks 16 on each floor level which can be constructed in any known manner such as extending girders between the columns, laying mesh and pouring concrete or they can, if desired, be pre-cast and lifted into place on the beams at the construction site.

The decks 16, 16 have a stairwell opening so that stairs 60 and 61, for instance, again of conventional construction, can be mounted therebetween. It is also contemplated that a railing such as 62 would be placed at the ends of each deck for safety purposes. Furthermore, the open space into which the decks are placed can accommodate an elevator shaft (not shown) if desired or required either by local building codes or by the height of the structure.

Considering briefly next the housing components 20, it will be seen that the same can be prefabricated apartments, for instance, of a type well known. An example of one of these is shown in FIG. 6 as 20a and it should be noted that trailers could be utilized with equally good results such as indicated at 20b. It should be noted here, however, that while residential units have been illustrated and described, the essential construction could be used for other purposes such as, for example, office or retail uses.

Turning next then to FIG. 7 for an examination of the manner in which the housing components are mounted on the beams, it will be seen that a first plate 31 is secured to the top of the beam 15 as by welding for instance. This plate has a through bore therein and has a second cover plate 32 overlying it and overlying the foot of the I beam 30. A threaded stud 33 and nut 34 are also provided so that when the nut and stud are tightened down the plate 32 will hold the I beam 30 in place. If more secure holding is desired, it is also possible to weld the I beam 30 onto the beam 15 although the method disclosed does permit quick and easy installation and removal of the housing units.

The top of the I beam 30 supports the housing component 20 and the bottom or floor of the component 20 may be welded to the I beam. While only one I beam has been shown, any number can be employed depending upon the requirements of weight which might exist with differing housing components.

Turning next then to FIG. 8 for a brief description of the method of attaching the housing unit to the columns 11, 12, 13 and 14, it will be seen that the wall 21 of the housing unit 20 has at least one through hole bored therein. A threaded stud 32 projects from the column 11 through this opening and has associated with it the conventional cover plates 40 and 41 and nuts 43, 43. It is a simple matter, therefore, to tighten these down and firmly secure the wall 21 to the column.

Again, only one such connection has been illustrated with it being understood that any number of these connections could be employed.

Turning next then to FIG. 9, it will be recalled that the upright columns 11, 12, 13, and 14 have been described as being hollow. The purpose of this is to enable utility connections such as gas, water, electricity, sewage, etc. to be carried inside the hollow columns. At each floor level an aperture 11a is provided in each column so that a branch can be taken off the particular utility desired and run into the floor of the housing component. Examples of these utility connections are shown in FIG. 9 and identified by the numerals 50, 51 and 52. Cover plates 53 and 54 are welded or otherwise secured to the column to hold and support the utility connections. In this fashion not only are the utility conduits 50, 51 and 52 protected from the elements but they are kept out of sight thereby achieving improved aesthetic effects.

In use of the improved structure the construction site will be prepared in the normal manner. The foundation F can then be poured and can be concrete or similar material. Columns 11, 12, 13 and 14 are then erected as shown in FIGS. 1 and 4 for instance. The cantilevered beams 15, 15 are then mounted on the columns so that their projecting outboard ends project beyond the outside edges of

the columns. The decks 16, 16 are then mounted on each pair of beams 15, 15 and as mentioned earlier, can either be built and poured at the site or could be prefabricated and lifted into place.

Following this, the stairs such as 60 and 61 and railing such as 62 are emplaced.

The I beams 30, 30 are then secured in place and at this time, assuming that the utility connections have been placed inside the hollow columns, it is merely necessary to lift a housing component such as 20a into place resting on the I beams. Following this the I beams will be secured to the bottom of the housing unit and the wall of the housing unit will be secured to the columns as previously described and as shown in FIGS. 7 and 8. Once this has been accomplished, the utility connections can be made as shown in FIG. 9 and described above and at that time, a completely ready-to-use housing unit has been constructed.

Turning next then to the modified form of the invention shown in FIG. 10, it will be seen that the broad principle of the invention is again employed with a slight variation to provide a building with a different outward appearance.

Specifically, two pairs of vertical, hollow, spaced apart columns 111, 112, 113 and 114 are again employed and are mounted on the foundation in the manner described above with regard to FIGS. 1 through 10.

Similarly, a pair of beams 115a and 115b are mounted on the vertical columns in the manner also described above and can support housing units such as indicated at 120. The second layer or story, however, involves the utilization of beams 115c and 115d which extend between and span the distance between columns 112 and 113 in the instance of beam 115d and columns 111 and 114 in the instance of beam 115c. It will be seen that this second set of beams run at right angles to the first and accordingly the housing units 120a which are supported on their cantilevered ends likewise run at right angles to the units 120, 120. It is contemplated that the beams supporting alternate stories will be disposed at right angles to each other so as to give a pleasing overall appearance differing somewhat from the appearance of the building shown in FIG. 1 for instance.

The method of attaching the housing units to the beams and to the columns, and the method of disposing the utility connections within the hollow columns are intended to be the same as those described above with regard to FIGS. 1 through 9.

Similarly, the open area bounded on its four corners by the upright columns provides the necessary space for the deck, stairs, etc.

Turning next then to FIGS. 11 and 12, a still further modification employing the basic principle of the invention is disclosed.

Thus, in this instance, six upright columns 211, 212, 213, 214, 215 and 216 are emplaced on the foundation or support so as to form the perimeter of a hexagon. The beams utilized in this form of the invention differ slightly from the beams used in the earlier discussed forms. Specifically, the beam 217 has a generally Y-shaped planar configuration including one relatively long leg 218 and a relatively short leg 219 projecting from approximately the midpoint of the leg 218. Thus, in this form of the invention, one end 218a is secured to column 216, for example. The opposed end 218b projects beyond column 212 as clearly shown in FIG. 11 and the leg is, of course, secured to column 212 in the manner described above. Projecting leg 219 of the beam 217 is secured to the column 211 and also has its end projecting outwardly therefrom. A second beam 230 is secured to the columns 213, 214 and 215 in similar manner. In this fashion, the projecting ends 218b of column 217 and 231 of column 230 provide a support for the housing unit 220 with, of course, the unit being secured to the beams and the columns in the manner described above.

It is believed apparent that upon mounting beam 240 on columns 214, 215 and 216 provision will be made

for mounting three housing units as is clearly shown in FIG. 12.

All successive stories could be constructed in this manner giving a basic triangular configuration to the building when viewed from the top, for instance. Variations can be obtained as shown in FIG. 12 by simply swinging beam 217, for instance, to the right and supporting it on columns 211, 212 and 213. Beams 230 and 240 would likewise be rotated and this framework would, once the housing units are in place, result in a building having the appearance of the building of FIG. 12 for instance.

It is believed apparent that further modifications employing the basic concept can be resorted to, present a variety of configurations, with the above noted variations being representative only and not intended to be exhaustive.

It should be noted that this method provide a relatively simple, yet efficient and economical method for rapidly constructing a building with a minimum of work required at the job site.

It can also be seen that the relatively simple manner of connecting the housing units to the beams and columns permits quick and easy removal for renovation or repair if required.

While a full and complete description of the invention has been set forth in accordance with the dictates of the patent statutes, it is believed apparent that modifications as to size and material could be resorted to such as, for example, to conform to local building codes without departing from the spirit hereof or the scope of the appended claims.

What is claimed is:

1. A building structure, comprising;

(A) a first pair of upright spaced apart columns;
(B) a first cantilevered unitary support beam secured to said first pair of columns with its end projecting freely beyond said columns

(1) whereby a first frame element having an H-shaped configuration when viewed in elevation is formed;

(C) a second pair of upright spaced apart columns that are disposed in parallel spaced apart relationship to said first pair of columns;

(D) a second unitary support beam secured to said second pair of columns with its ends projecting beyond said columns

(1) whereby a second frame element having an H-shaped configuration when viewed in elevation is formed;

(E) attachment means carried by said columns and said beams;

(F) a plurality of prefabricated housing units mounted on the outboard ends of said support beams interconnecting said beams and spanning the distance therebetween and secured to said attachment means;

(G) a deck spanning the open space between said first and second H-shaped frame elements and said housing elements; and

(H) the top, bottom, side and end surfaces of each said housing unit forming the weather faces of the completed building structure.

2. The structure of claim 1 further characterized by the presence of

(A) at least one additional support beam similarly secured to each said pair of columns at a higher elevation than said first and second beams;

(B) additional prefabricated housing units carried by said additional support beams; and

(C) the vertical distance between said support beams

being greater than the height of said housing units

(1) whereby said housing units are spaced from each other when mounted on said support beams.

3. A building frame, comprising;

(A) a plurality of upright columns mounted on a supporting surface and spaced from each other;

(B) a plurality of support beams

(1) having a generally Y-shaped planar configuration and

(2) arranged about a central axis

(3) each having each of their legs secured to a separate column with the ends of two said legs projecting a substantial distance beyond the column to which they are secured;

(C) adjacent support beams having at least one leg secured to a common column; and

(D) at least one projecting leg of each support beam being parallel to and spaced from one projecting leg of its adjacent support beam.

4. A building structure, comprising;

(A) a first pair of upright spaced apart columns;

(B) a first cantilevered support beam secured to said first pair of columns with its ends projecting beyond said columns

(1) whereby a first H-shaped frame element is formed;

(C) a second pair of upright spaced apart columns that are disposed in parallel spaced apart relationship to said first pair of columns;

(D) a second cantilevered support beam secured to said second pair of columns with its end projecting beyond said columns

(1) whereby a second H-shaped frame element is formed;

(E) attachment means carried by said columns and said beams;

(F) a plurality of prefabricated housing units mounted on the outboard ends of said support beams and attached to said attachment means;

(G) a deck spanning the open space between said H-shaped frame elements and said housing elements; and

(H) at least one additional pair of cantilevered support beams

(1) secured to said upright support columns at right angles to and at a higher elevation than said first and second support beams.
